UNITED STATES PATENT OFFICE.

RUSSELL JENNINGS, OF DEEP RIVER, CONNECTICUT.

IMPROVEMENTS IN MACHINERY FOR SWAGING THE HEADS OF SCREW-AUGERS.

Specification forming part of Letters Patent No. 56,869, dated July 31, 1866; antedated January 31, 1866.

To all whom it may concern:

Be it known that I, RUSSELL JENNINGS, of Deep River, county of Middlesex, and State of Connecticut, have invented a new and useful Machine for Swaging or Forming the Heads of Screw-Augers; and I do hereby declare that the following is a full, clear, and exact description thereof, which will enable those skilled in the art to make and use the same, reference being had to the accompanying drawings, forming part of this specification, in which—
Fig. 1 is a front view of my invention; Fig. 2, a transverse vertical section of the same taken in the line xx , Fig. 1; Fig. 3, a plan or top view of an auger-head formed or swaged according to my invention; Fig. 4, a face view of the die used for forming or swaging the head. Fig. 5 represents a detached view of one of the dies, l , the other die, l' , being the counterpart thereof.

Similar letters of reference indicate like parts.

This invention relates to a new and useful improvement in swaging or forming the heads of screw-augers; and it consists in a novel arrangement of a die and mold, and the manner of operating the die, as hereinafter fully shown and described, whereby the desired work may be performed in a very rapid manner and with great perfectness.

A A represent two horizontal bars, which constitute the bed of the machine, said bed being supported at a suitable height by legs $a a$. To each side of the bed there are secured uprights b , the upper ends of which are connected by a cross-piece, c . Between the upper parts of these uprights there are secured bearings d , in which a shaft, B , is fitted horizontally, said shaft having a crank or eccentric upon it, to which a rod, C , is connected, the latter having a rod, e , connected to it by a joint, f , as shown clearly in Fig. 2.

The lower end of rod e has a die, D , formed on it, or receives the portion on which the die is cut.

On one end of the shaft B there is placed loosely a wheel, E , having two pins, $g g$, projecting from its inner side. There is also placed on said shaft a wheel, F , the latter being on a square portion, h , on the shaft, so that it may slide thereon, and at the same

time, whenever turned, communicate motion to the shaft.

The wheel F has a projection, i , on its side, which faces the wheel E , said projection being at the edge of wheel F , and having one end beveled, as shown in Fig. 1, and from the opposite side of said wheel a pin, j , projects.

G is a bar which extends across the face of the wheel F , and has its end bent inward and inclined to form a lip, a^* , for the projection i of the wheel F to come in contact with, as will be hereinafter explained.

H is a horizontal sliding rod fitted in bearings k , attached to the uprights b , and connected at its outer end to a pendent lever, I , as shown in Fig. 1.

On the outer end of shaft B there is keyed a wheel, J , having a notch, l , in its periphery, and K is a spring attached to one of the uprights b , and having its free or disengaged end bearing against the periphery of wheel J .

L represents a mold or female die, composed of two parts, $l l'$, one part, l , being fixed or stationary, and the other part, l' , being allowed to move or slide freely. This part, l' , is operated by a toggle, M , the joint of which has a pendant, N , attached, which extends down between the bars A A of the bed, and is connected at its lower end to a lever, O , one end of which is secured by a joint, m , to one of the legs or supports a of the bed, and the other end connected by a joint to the lower end of vertical rod P , which passes up through a guide, n , attached to one of the uprights b .

By raising the rod P the toggle M will be actuated to draw back the movable part l' of the mold or female die L , as shown in Fig. 1.

The die L receives the auger to be operated upon. The twist is given to the auger, and its end on which the head or cutting portion is to be swaged or formed is struck up in proper shape prior to the auger being fitted in the die L , between the two parts $l l'$ thereof, and these parts are formed with a female screw, which grasps the screw formed by the twist of the auger, and when the part l' is closed against the part l the auger is retained firmly in position, the end o of the auger above its twist being in a cylindrical part of the mold or die L . (See Fig. 2.)

Each of the pieces $l'l'$ has a projection l^x , which, forming part of the mold, projects into its fellow-piece, so as to make the forming-thread continuous. Were the projection l^x to be attached in the other die, into which it projects, it would cause that portion of the mold so far to inclose the twist of the auger as to prevent its withdrawal; but by causing each section of the die to include a portion of its counterpart the projecting portion is withdrawn and permits the auger to be raised from its bed.

The heading-die D may be described as formed of a cylinder equal in diameter to the interior of the upper part of the mold L, in which it works, provided with a central hole, p , to receive the pindle r of the auger-head, and having a recess, s , at opposite points in its side, to form the spurs $t t$ of the auger-head, and having its face recessed, as shown at $u u$, to form projecting edges or floor-lips $v v$, tangential with the pindle, on which cutting-edges are formed to take out, when the auger is at work, the wood within the circular cut made by the lips $t t$. (See Figs. 3 and 4.)

The operation is as follows: The wheel E, during the operation of the machine, has a continuous rotary motion, and the operator, by raising the rod D, throws back the part l' of the die L, and then inserts an auger between the parts $l'l'$, the auger being properly heated. The rod D is then shoved down and the part l' closed against the part l , the auger being firmly secured within the mold or die. The lever I is then actuated so that the rod H will bear against the wheel F, and move it toward the wheel E, until one of the pins g of said wheel will come in contact with the projection i of the wheel F, when the latter is turned, and with it the shaft B, and the rod C forced down, and consequently the heading-die D, the latter acting upon the auger and forming or swaging the head thereon.

The work is done with one revolution only of shaft B, the beveled end of the projection i , at the termination of the revolution of wheel F, coming in contact with the inclined lip a^x , which causes the wheel F to be moved from wheel E, and its projection i thrown out of the reach of the pins g of E, the pin j of wheel F coming in contact with a shoulder, b^x , on

the cross-piece c , to prevent a farther movement of F, by its momentum, and the spring K engaging with the notch l , to prevent any backlash or back movement of the shaft B. The rod P is then raised and the die L opened, the auger removed, and another one placed in the die, the latter closed, and the lever I actuated to throw the wheel F toward the driving-wheel E, the pins $g g$ of which come in contact with the projection i of wheel F, and the succeeding auger is headed as the previous one.

By this device augers may be headed or have their cutting-edges formed on them with great rapidity and in a perfect manner. There is no welding of parts together to form the cutting-edges of the head, the latter being swaged from a single piece of metal which forms the end of the screw or twist of the auger.

I do not confine myself to any particular form or pattern for the head of the auger, the shape of the end of the plunger and of the upper cross-piece of the female die varying according to the style and form of auger required.

I do not claim the principles of swaging as in bolt heads, nails, and spikes, but

I do claim—

1. The operating of the heading-die by the rotating shaft B, through the medium of the loose driving-wheel E, provided with the pins g , the sliding wheel F, placed on a square shaft, B, and provided with the projection i , beveled at one end, in connection with sliding rod H, and the fixed inclined lip a^x , all arranged to operate substantially as set forth.

2. The forming-die, consisting of the portions $l'l'D$, constructed and operating substantially as described.

3. The combination of the heading-die D, mold or female die L, toggle M, and driving or operating mechanism, so arranged that the driving-shaft B may, at the will of the operator, be connected with and disconnected from the continually rotating driving-wheel E, substantially as described.

RUSSELL JENNINGS.
